UNITED STATES PATENT OFFICE.

CHARLES W. ALLEN, OF MARTIN, SOUTH DAKOTA.

GRADE-CROSSING PROTECTOR.

Application filed March 25, 1924. Serial No. 701,809.

To all whom it may concern:

Be it known that I, CHARLES W. ALLEN, a citizen of the United States of America, residing at Martin, in the county of Bennett and State of South Dakota, have invented certain new and useful Improvements in Grade-Crossing Protectors, of which the following is a specification.

My invention relates to devices for protecting grade crossings, and more especially to devices for bringing motor vehicles and the like to a low rate of speed to pass safely over dangerous crossings.

An important object of my invention is the provision of a device of the above mentioned character which will allow vehicles going at a low rate of speed to pass, but which will positively prevent vehicles driven at an excessive rate of speed from passing.

Another object of my invention is to provide a device of this character which will be entirely automatic in its operation and which will automatically reset itself.

A further object of my invention is the provision of a device of this character which will be simple in construction, strong and durable.

Other objects and advantages of my invention will be apparent during the course of the following description.

In the accompanying drawings forming a part of this specification and in which like numerals are employed to designate like parts throughout the same:

Figure 1 is a plan view, partly diagrammatic, showing my invention installed at a grade crossing;

Figure 2 is a longitudinal sectional view taken on line 2—2 of Figure 1

Figure 3 is a perspective view of one of the obstruction members, and,

Figure 4 is a fragmentary detail view showing the method of assembling the obstruction member and guide rods.

In the drawings, wherein for the purpose of illustration is shown a preferred embodiment of my invention, the numeral 5 designates a railroad track or the like, which is intersected by the highway 6. Arranged at a substantial distance from each side of

the track are division posts 7 which divide the road and separate vehicles going in opposite directions. My protection devices are adapted to be arranged at each side of these posts and in the center of the paths of vehicles approaching or leaving the crossing. Each of these protection devices consists of a casing 8 which is adapted to be embedded in the roadbed so as to lie flush with the level of the highway. This casing is long and relatively narrow, and has inclined end walls 9 which slope downwardly and outwardly and the bottom or lower end of this casing is preferably left open.

In installing the casing, a pit 10 is dug in the roadbed and the casing placed in the pit with its upper surface flush with the road, and the earth, or other roadbed material is then packed tightly about the casing. The inclined end walls serve to lock the casing in the ground and prevent it from being torn out bodily. The upper surface of the casing 8 is provided with a longitudinally extending slot or opening 11 which is preferably surrounded by a horizontal flange 12 to strengthen the casing and steady it in the ground. Arranged midway of the slot is a transverse pin 13 which is rigidly mounted in the sides of the opening of slot 11. Pivoted upon this pin is the automatic obstruction or stop member 14 which is pivoted above its center of gravity so as to be normally in an upright position.

In the preferred embodiment of my invention, this obstruction member is formed from a single piece of any suitable material, and is provided with cutaway portions 15 in its upper end to form the prongs 16. These prongs slope downwardly and the top portion of the stop member 14 has the appearance of an arrow head. By cutting out portions of the upper portion of the member 14, the lower portion is rendered much heavier in proportion and as a consequence, the member 14 will more readily assume its upright position. The lower portion of the member 14 is also cut away at 17, to form downwardly extending prongs 18.

Extending across the cutaway portions 15 are guide rods 19 which form a con-

tinuation of the sides of the member 14. These rods 19 are provided at their upper ends with cross pieces 20 which are adapted to fit in the cut out portions 21 of the 5 prongs 16 and which will lie flush with the top surface of the prongs. The ends of the prongs 16 are also provided with sockets 22 for the reception of the stems of the rods 19 which will lie flush with the 10 sides of the member 14 and with the ends of the prongs 16. The upper surface of the cut out portions 21 and the lower surface of the cross pieces 20 are provided with corresponding serrations 23 which 15 form a firm joint. Openings 24 are provided to receive bolts 25 to fasten the rods 19 to the prongs. The rods are fastened at their lower ends to the side of the members 14 by means of the bolts 26. These 20 rods 19 are of slight construction and are formed of brittle material. A pit 27 may be provided beneath the opening 11, for the reception of débris, so that it will not interfere with the free movement of the member 14 within the pit or cavity 10, and this 25 pit should be provided with a drain 28. Auxiliary guide posts 29 may be provided in alignment with the post 7 so as to force motor vehicles to pass over the protecting 30 device.

In operation, a vehicle, to reach the crossing must pass over this automatic stopping device, and in so doing its axle will strike the guide rods 19 and tilt the member 14 35 which will automatically right itself when the vehicle has passed. Should the vehicle be moving at an excessive rate of speed, the impact will break the brittle guide rod 19 and the prong 16 will engage the axle 40 and either stop or wreck the car. But even should the guide rod withstand the impact, the force of the blow will revolve the member 14 about its pivot and the prongs 18 will engage the under works of the car or 45 the rear axle and the car will be brought to a stop before reaching the crossing. The speed at which a car is allowed to pass is determined by the size and strength of the guide rods 19.

50 A set of these protection devices is arranged on each side of the track so that a car will not get up speed, after passing the first one, but will continue over the crossing slowly in order that it may not be 55 stopped or injured at the other stopping device.

It is to be understood that the form of my invention herewith shown and described is to be taken as a preferred example of 60 the same, and that various changes in the shape, size, and arrangement of parts may be resorted to without departing from the spirit of my invention or the scope of the subjoined claims.

65 It is evident that the construction of my

device is such as to permit animal drawn vehicles and loose stock to pass without hindrance or injury thereto.

Having described my invention what I claim as new and desire to protect by Letters Patent is:

1. In a device of the character described, an obstruction member being normally arranged in the path of vehicles, means whereby said obstruction member will be automatically removed from the path of a slowly moving vehicle, and means whereby said obstruction member will not be removed from the path of a fast moving vehicle but will engage and stop the same. 75

2. In a device of the character described, an obstruction member, said obstruction member being normally arranged in the path of vehicles, means whereby said obstruction member will be removed from the path of a slowly moving vehicle, means whereby said obstruction member will be automatically returned to its normal position in the path of vehicles, and means whereby said obstruction member will not 80 be removed from the path of a fast moving vehicle but will engage and stop the same. 85

3. In a device of the character described, an obstruction element pivotally mounted in the path of vehicles, the greater portion of the obstruction element being arranged below the pivot point whereby the obstruction element is normally arranged in its vertical position means whereby the obstruction element is rotated about its pivot, when 100 struck by a slowly moving vehicle, so as to be removed from the path of the vehicle, and means whereby the obstruction device will engage, and obstruct the passage of a fast moving car, due to the inertia of the heavier 105 portion of the obstruction element which is arranged below the pivot point. 95

4. In a device of the character described, an obstruction member mounted in the path of vehicles, a prong formed on the upper portion of said obstruction member, and a frangible guide rod attached to said prong and adapted to be broken by the impact of a fast moving vehicle to allow the prong to engage said vehicle and obstruct its passage. 110 115

5. In a device of the character described, an obstruction member pivotally mounted in the path of vehicles, said obstruction member being normally arranged in its upright position, the upper portion of said obstruction device being cut away to form prongs, and frangible guide rods extending across said cutaway portion and detachably connected with said prongs, said guide rods being adapted to be broken by the impact 125 of a fast moving vehicle to allow the prongs to engage the vehicle, the lower portion also being cut away to form prongs, whereby in the event that the guide rods should withstand the impact, the obstruction member 130

would be rotated about its pivot and the second named prongs would engage the vehicle.

10 mounted in said slot, said obstructing element being adapted to obstruct the passage of fast moving vehicles but adapted to be depressed within said casing by slowly moving vehicles.

6. In a device of the character described, a casing adapted to be embedded in the roadway, said casing having downwardly and outwardly inclined end walls, said casing also being provided with a longitudinally arranged slot and an obstruction element

15 In testimony whereof I affix my signature.

CHARLES W. ALLEN.
